STAMPED RATCHET DIE HEAD

Filed Sept. 8, 1928

UNITED STATES PATENT OFFICE

RALPH E. HYDE, OF CLEVELAND, OHIO, ASSIGNOR TO THE OSTER MANUFACTURING COMPANY, OF CLEVELAND, OHIO, A CORPORATION OF OHIO

STAMPED RATCHET DIE HEAD

Application filed September 8, 1928. Serial No. 304,784.

The present invention relates, as indicated, to a stamped ratchet die stock, and the primary object of the invention is to provide a ratchet die stock made up, to a large extent of stamped parts. Further objects of the invention will appear as the description proceeds. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is an elevation of a stock constructed in accordance with the present invention; Fig. 2 is a longitudinal section thereof taken substantially on the line 2—2 of Fig. 1; Fig. 3 is a side elevation of the handle member; Fig. 4 is a section taken substantially on the line 4—4 of Fig. 2, and looking in the direction of the arrows; and Fig. 5 is a broken front elevation of the handle member.

Referring more particularly to the drawings, it will be seen that the reference numeral 10 indicates a substantially cylindrical member formed of stamped sheet metal, said member being hollow, and open at its opposite ends. At its one end, said member 10 is formed with an outwardly projecting annular flange 11. A die head 12 provided with slots 13 for receiving chasers or cutters 14 is secured to said flange by means of screws 15, or equivalent securing means.

Said member 10 is formed, adjacent its end opposite the flange 11, with a plurality of longitudinally extending, equidistantly spaced depressions 16, said series completely circumscribing said member 10. As will be obvious, the depressions 16 define between them, a series of equidistantly spaced teeth 17 (see Fig. 4).

A handle member 18 is formed in its one end with a socket 19 screw threaded as at 20 for the reception of an operating bar. The

opposite end of said member is cylindrical in form as indicated at 21, and is formed with a bore 22 adapted to receive the grooved end of the member 10. When the handle 18 is in place on the member 10, the bore thereof completely encloses the grooves or depressions 16 and the teeth 17. 55

Within an open portion 23, which may be considered a portion of the bore 22, there is mounted a pivot pin 24, the pin being positioned in paraxial relation to said member 10. A pawl 25 is mounted on said pin, and said pawl is formed with substantially identical opposite ends 26 and 27. Substantially midway between its ends, said pawl is formed with a cam 28 having a notch 29 in its topmost surface. A spring leaf 30 is mounted within said open portion 23 and has a nose 31. As will be obvious, the pawl 25 may be set in the position illustrated, in which position the nose 31 of the spring leaf 30 bears against the face 32 of the cam 28 to hold the end 27 of said cam resiliently in engagement with the teeth 17 of the member 10. Correspondingly, the pawl may be set in such a position that the nose 31 of the spring leaf 30 will hold the end 26 of said pawl resiliently in operative relation with the teeth 17 of the member 10. On the other hand, the pawl 25 may be set in such a position that the nose 31 of the leaf 30 will enter the notch 29 in the cam 28 to hold both the pawl ends out of cooperative relation with the teeth 17. 70 75

In order to retain the handle 18 on the cylindrical member 10, I provide said cylindrical member with a punched up lug 33 which is adapted to be received in an annular groove 34 formed in the portion 21 of the handle member. Said lug 33 is formed in advance of the grooves 16, and said annular groove 34 is correspondingly located in the portion 21. An entry slot 35 opens from said groove 34 to the front face of the portion 21 of the handle member 18 to permit the passage of the lug 33 into and out of said groove. Said entry slot is so located that, when the lug 33 is in registry with said slot an end 26 or 27 of the pawl 25 will be in registry with one of the grooves 16. This 85 90 95 100

arrangement insures against accidental removal of the handle member 18 from the cylindrical member 10 at all times, since, when the lug 33 is in registry with the slot 35, 5 the pawl 25 will normally be engaged in one of the slots 16, thus preventing material axial movement of the handle member 18 with respect to the member 10, and when the end of said pawl is in registry with one of 10 the teeth 17, the handle member is held against axial movement by the engagement of the lug 33 in the slot 34. Thus, in order to remove the handle from the cylindrical member 10, it is necessary to bring the lug 33 into registry 15 with the slot 35, and to move the pawl 25 into such a position that neither one of its ends 26 or 27 will engage with the cylindrical member 10.

Other modes of applying the principle of 20 my invention may be employed instead of the one explained, change being made as regards the invention herein disclosed, provided the means stated by any of the following claims or the equivalent of such stated 25 means be employed.

I therefore particularly point out and distinctly claim as my invention:

1. A die stock comprising a substantially cylindrical sheet metal member, an integral 30 annular flange at one end of said member, said member being formed with a series of equally spaced, longitudinally extending stamped depressions about its periphery adjacent its opposite end, said depressions defining teeth therebetween.

2. A die stock comprising a substantially cylindrical sheet metal member, an integral annular flange at one end of said member, said member being formed with a series of 40 equally spaced, longitudinally extending stamped depressions about its periphery adjacent its opposite end, said depressions defining teeth therebetween, a head, means securing said head to said flange, and a handle 45 having a bore adapted to receive the grooved end of said member and to enclose said depressions.

3. A die stock comprising a substantially cylindrical sheet metal member, an integral 50 annular flange at one end of said member, said member being formed with a series of equally spaced, longitudinally extending depressions about its periphery adjacent its opposite end, said depressions defining teeth 55 therebetween, a head, means securing said head to said flange, a handle having a bore adapted to receive the grooved end of said member, and a pawl pivoted in said bore and adapted to engage in said depressions.

4. A die stock comprising a substantially cylindrical sheet metal member, an integral annular flange at one end of said member, said member being formed with a series of 60 equally spaced, longitudinally extending 65 depressions about its periphery adjacent its

opposite end, said depressions defining teeth therebetween, a head, means securing said head to said flange, a handle having a bore adapted to receive the grooved end of said member, a double-ended pawl pivoted in said bore in registry with said depressions, a cam on said pawl, and means mounted in said bore and bearing on said cam, said means being adapted to hold a selected end of said pawl in cooperative relation with said depressions. 70

5. A die stock comprising a substantially cylindrical member, a head secured to said member, a handle provided with a bore adapted to receive said cylindrical member, cooperating means on said handle member and said cylindrical member effective in all relative positions but one of said handle and said cylindrical member to prevent removal of said cylindrical member from said bore, and spring pressed means normally effective in said one relative position to prevent removal of said cylindrical member from said bore, said spring pressed means being adapted to be rendered ineffective to prevent such removal. 80

6. A die stock comprising a substantially cylindrical sheet metal member, an integral annular flange at one end of said member, said member being formed with a series of 85 equally spaced, longitudinally extending depressions about its periphery adjacent its opposite end, said depressions defining teeth therebetween, a head, means securing said head to said flange, a handle having a bore 90 adapted to receive the grooved end of said member, a pawl pivoted in said bore and adapted to engage in said depressions, said pawl cooperating with said depressions to prevent removal of said cylindrical member from said bore when said pawl is in registry with any one of said depressions, and separate means preventing such removal at other times, but ineffective to prevent such removal in one position in which said pawl enters a 100 depression. 105

7. A die stock comprising a substantially cylindrical sheet metal member, an integral annular flange at one end of said member, said member being formed with a series of 110 equally spaced, longitudinally extending depressions about its periphery adjacent its opposite end, said depressions defining teeth therebetween, a head, means securing said head to said flange, a handle having a bore 115 adapted to receive the grooved end of said member, a pawl pivoted in said bore and adapted to engage in said depressions, said pawl cooperating with said depressions to prevent removal of said cylindrical member from said bore when said pawl is in registry with any one of said depressions, and further cooperable means carried by 120 said handle and cylindrical member and normally preventing such removal at other 125 130

times, but ineffective to prevent such removal in one position in which said pawl enters a depression.

8. A die stock comprising a substantially cylindrical sheet metal member formed with a series of equally spaced, longitudinally extending depressions about its periphery adjacent its opposite end, said depressions defining teeth therebetween, a head secured to said cylindrical member, a handle having a bore adapted to receive the grooved end of said member, a pawl pivoted in said bore and adapted to engage in said depressions, said pawl cooperating with said depressions to prevent removal of said cylindrical member from said bore when said pawl is in registry with any one of said depressions, and further cooperable means carried by said handle and cylindrical member and normally preventing such removal at other times, but ineffective to prevent such removal in one position in which said pawl enters a depression.

9. A die stock comprising a substantially cylindrical sheet metal member formed with a series of equally spaced, longitudinally extending depressions about its periphery adjacent one end, said depressions defining teeth therebetween, a head, means securing said head to the opposite end of said cylindrical member, a punched-up lug on the surface of said cylindrical member between said teeth and said head, a handle having a bored cylindrical portion adapted to receive said cylindrical member, said portion being formed with an internally open annular groove therein adjacent its forward face, and with an entry opening through said face into said groove, said lug being adapted to enter said groove through said slot, a pawl in said bore, and means urging said pawl into said depressions, said slot and said lug being so located that they register only when said pawl registers with one of said depressions.

Signed by me this 4 day of September, 1928.
